(57) **CLAIM**

The ornamental design for a semi-flush air data sensor, as shown and described.

DESCRIPTION

FIG. 1 is a perspective view of a semi-flush air data sensor embodying our new design;

FIG. 2 is an outer side view thereof;

FIG. 3 is a front view thereof;

FIG. 4 is a rear view thereof;

FIG. 5 is a top view thereof, the bottom view being a mirror image of the top view; and,

FIG. 6 is an innerside view thereof; the dotted line representations form no part of the claimed design.
